UNITED STATES PATENT OFFICE

LAURENCE E. TOPHAM, OF WENHAM, AND ALFRED R. MORRILL, OF BEVERLY, MASSACHUSETTS, ASSIGNEES TO UNITED SHOE MACHINERY CORPORATION, OF PATERSON, NEW JERSEY, A CORPORATION OF NEW JERSEY

METHOD OF MAKING SHOES

Application filed December 18, 1926, Serial No. 155,624. Renewed March 21, 1929.

The present invention relates to those operations which are performed progressively along the bottom margin of a shoe while supported upon a last.

5 The object of the invention is to facilitate certain of these operations and particularly the operations of sewing the inseam of a welted shoe and of trimming off the surplus materials extending from the inseam, or as it 10 is usually termed in the art, trimming the inseam, and enable these operations to be performed in an accurate and reliable manner with uniform results and without any special care or skill on the part of a workman.

15 With this object in view the invention contemplates presenting a lasted shoe successively to an inseam sewing mechanism and to an inseam trimming mechanism, guiding the shoe during each operation to cause the point 20 of operation to follow a predetermined outline and imparting predetermined relative tipping positioning movements to the shoe and operating means as the point of operation is transferred around the shoe to locate 25 the inseam and the inseam trimming cut in predetermined relation to the shoe sole and to each other.

It is desirable in the manufacture of a shoe that the inseam be located in a plane parallel 20 to the surface of the insole and it is also desirable that the inseam trimming cut be made at a uniform distance from the seam both inside and outside of the seam all around the shoe. These results can be uniformly attained by the use of the present invention. 35 Also the steps of the method are such that they can be carried out by automatic machinery and thus the amount of manual labor required in the manufacture of a shoe reduced 40 with a consequent reduction in the cost of manufacture and the elimination of errors due to lack of skill or care on the part of workmen.

45 Preferably the shoe is guided during each operation by engaging a guiding device in the inseam channel of the sole, since the shoe can be guided conveniently and accurately in this manner both during the sewing and during the trimming, and the tipping positioning movements can be readily imparted to the

shoe without liability of bodily displacement.

In addition to the features of invention above referred to the present invention also consists in the improved methods of shoe manufacture hereinafter described and 55 claimed, certain of which are not limited to the operations of inseam sewing and inseam trimming.

The invention will be readily understood 60 from the following description taken in connection with the accompanying drawings in which are illustrated an automatic inseam sewing machine and an automatic inseam trimming machine which may be utilized in carrying out the several steps of the present 65 invention.

In the drawings Fig. 1 is a view in front elevation of the inseam sewing machine; Fig. 2 is a view in side elevation of the machine shown in Fig. 1 looking from the right; Fig. 3 is a plan view of the machine; Fig. 4 is a view in side elevation of the upper portion of the machine looking from the right and illustrating the sewing mechanism and the jack; Fig. 5 is a detail view in side elevation and 70 partly in section of the parts of the sewing mechanism adjacent the point of operation illustrating the manner in which the shoe is guided and presented to the sewing mechanism; Fig. 6 is a detail view illustrating the 75 supporting mechanism for the jack, the mechanism for moving the jack to present the shoe properly to the sewing mechanism and certain associated parts; Fig. 7 is a detail view in side elevation of a portion of the jack supporting and actuating mechanism; Fig. 8 is a view 80 similar to Fig. 6 with certain of the parts removed to show the structure of other parts more clearly; Fig. 9 is a detail sectional plan view of a portion of the mechanism for driving the pattern cam shaft and for varying the speed of the shaft; Fig. 10 is a view in front elevation of the inseam trimming machine; Fig. 11 is a view in side elevation of the 85 machine illustrated in Fig. 10 looking from the left; Fig. 12 is a view in front elevation of the head or upper portion of the machine which contains the inseam trimming mechanism; Fig. 13 is a view in side elevation of the 90 head of the machine with a portion of the 95

casing cut away; Fig. 14 is a detail view taken substantially on the line 14—14 of Fig. 13; Fig. 15 is a view in vertical section of the head of the machine; Fig. 16 is a plan view with certain parts broken away and certain parts shown in section of the portion of the machine below the head; Fig. 17 is a view in front elevation, partly in section, illustrating particularly the driving connections for the machine; Fig. 18 is a view, partly in side elevation and partly in vertical section, of substantially the mechanism shown in Fig. 17; Fig. 19 is a view in side elevation illustrating the mechanism for supporting and actuating the jack; Fig. 20 is a detail view, partly in side elevation and partly in section, illustrating a portion of the mechanism shown in Fig. 19; Fig. 21 is a detail view illustrating in side elevation a portion of the stop mechanism; Fig. 22 is a detail view of a portion of the mechanism shown in Fig. 18 illustrating particularly the clutch of the auxiliary mechanism which is thrown into operation from the stop motion and which acts after the inseam trimming mechanism has been brought to rest; and Fig. 23 is a detail plan view illustrating a portion of the auxiliary mechanism, the tripping lever from which the stop motion is thrown into operation, and the connections for throwing the auxiliary mechanism out of operation.

In utilizing the present invention in the manufacture of shoes to facilitate the inseam sewing and inseam trimming operation the lasted shoe is first presented to an inseam sewing mechanism and during the sewing operation the shoe is guided in any suitable way as by the engagement of a channel guide with the channel or rib of the insole to cause the inseam to follow a predetermined outline and simultaneously the position of the shoe with relation to the stitch forming devices is controlled by imparting relative tipping movements to the shoe and stitch forming devices predetermined as to time and extent to cause the stitches of the inseam to be in the proper plane with relation to the plane of the insole.

At a later stage in the manufacture the shoe is presented to an inseam trimming mechanism and during this operation it is again guided in any suitable way as by a channel guide to cause the point of operation to follow a predetermined outline which may be the same or substantially the same as that followed by the inseam, and simultaneously the relative position of the shoe and trimming mechanism are again controlled by imparting relative tipping movements to the shoe and trimming mechanism predetermined as to time and extent to cause the trimming cut to be made at the desired distance from the seam on both sides of the seam at all parts of the shoe.

The inseam sewing and inseam trimming

machines illustrated in the drawings are automatic in their action and are designed to guide a shoe so as to cause the point of operation to follow the outline of the channel of the insole and to impart tipping positioning movements to the shoe as the point of operation is transferred around the shoe. These machines therefore are well adapted for use in practicing the present invention. The cam paths of each machine are designed with reference to the style of shoe to be operated upon and with reference to the cam paths of the other machine so that the final product of the two machines are shoes, the inseams and inseam trimming cuts of which are located uniformly in predetermined relation to the shoe sole and to each other. The inseam sewing machine has the same general construction and mode of operation as the machine disclosed in the patent to Laurence E. Topham, granted Feb. 8, 1927, No. 1,616,713, and the inseam trimming machine has the same general construction and mode of operation as the machine disclosed in the application of Alfred R. Morrill, filed Feb. 2, 1920, Serial No. 355,583.

The inseam sewing machine illustrated in Figs. 1 to 9 comprises a sewing mechanism which, as a whole, is fixed in position, and a shoe supporting jack which is mounted in the machine so as to be capable of being moved to transfer the point of operation around the shoe and to be tipped and turned so as to locate the stitches of the inseam in the desired position with relation to the surface of the insole. As the point of operation is transferred around the shoe the shoe is guided by devices including a guide which engages the channel of the sole and tipping and turning movements predetermined as to time and extent are imparted to the shoe through connections to the jack from a pattern cam shaft. The inseam is thus caused to follow a predetermined outline and the stitches of the inseam are caused to have a predetermined location with relation to the surface of the insole. The sewing mechanism and the mechanism for moving the jack are driven in unison during the sewing of a seam and are stopped automatically by the action of suitable stopping devices at the completion of the seam. After a seam is completed the operator disengages the shoe from the sewing mechanism and then throws into operation mechanism which acts to drive the jack moving mechanism independently of the sewing mechanism to return the jack to its initial or starting position. When the jack reaches this position this driving mechanism is automatically thrown out of operation.

The sewing mechanism of the machine illustrated in Figs. 1 to 9 has the same construction, arrangement and mode of operation of the various parts as the machine illustrated and described in application Serial

No. 260,419, filed October 31, 1918, in the name of Alfred R. Morrill, one of the present applicants. This machine comprises a curved hook needle 24, a looper 26, a thread finger 28, a channel guide roll 30, and a welt guide 32. The needle, the channel guide roll and the welt guide are all mounted to reciprocate in the line of feed and the channel guide roll is rotated in a direction to feed the work during the back feed thereof, these parts operating in timed relation to each other to feed the work continuously through the machine. The parts of the sewing mechanism are all actuated from a sewing cam shaft 34.

The jack comprises a spindle 36, a toe supporting arm 38 rigid with the spindle and a heel supporting arm 40 pivoted to the spindle. The lower end of the spindle is secured to a hemispherical shell 42 which is connected by means of a gimbel joint to a wheel 44 rotatably mounted in the forward ends of supporting arms 46. These arms project from a yoke 48 which is pivotally connected to a yoke 50 so as to swing in a vertical plane. The yoke 50 is pivotally connected with a link frame 52 to swing in a horizontal plane, and the link frame is pivotally connected with the end of a supporting arm 54 pivotally mounted upon a vertical shaft 56 and is also pivotally connected with the end of a second supporting arm 58 pivotally mounted upon a vertical stud 60. The supporting arms 54 and 58 are of substantially the same length and the yoke 50 is pivotally connected with the link frame 52 at substantially the central point of the link frame. The yoke 50 thus is supported vertically but is free to move forwardly and rearwardly and to swing in a horizontal plane about its pivotal connection with the link frame, this connection moving substantially in a straight line perpendicular to the vertical plane of the line of feed of the machine during the forward and rearward movements of the yoke. In order to support the jack spindle and at the same time to permit it to move vertically to accommodate itself to the necessary variations in the vertical position of the shoe, a coiled spring 62 is connected at one end with an arm on the yoke 50 and at its other end with an arm on the yoke 48.

During the sewing operation the shoe is held positively to the machine at all times during each cycle of operations by the needle, welt guide and channel guide roll. Relatively slight vertical movements are imparted to the shoe by the action of the spring 62 on the jack and by the engagement of the channel guide roll and welt guide with the shoe, these parts acting as guides on the shoe. The required tipping movements are imparted to the shoe by devices acting on the jack spindle to move the lower end of the spindle forwardly, rearwardly and laterally of the machine in horizontal directions, and the lateral turn-

ing movements are imparted to the shoe by devices acting on the jack spindle to rotate the spindle. Because of the fact that the shoe is held at all times at the point of operation by the needle, channel guide roll and welt guide the tipping and turning movements are caused to take place about the point of operation.

The lateral tipping movements of the shoe are produced by the forward and rearward swinging movements of the arm 54 which through the connection described between the arm and the lower end of the jack spindle impart forward and rearward movements to the lower end of the spindle, thereby tipping the jack laterally. A cam roll supporting lever 64 is pivoted at one end by means of a stud 66 to the arm and connected at its opposite end by a link 68 with a stationary arm 70, said arm being formed on a bracket secured to the frame of the machine. The lever 64 carries a cam roll which engages in a cam groove 72 in a cam disk 74 mounted on a cam shaft 75 which, for the sake of convenience, will be hereinafter termed the pattern cam shaft. By the action of the cam groove 72 the lever 64 is actuated to impart forward and rearward swinging movements to the arm 54 and thereby to impart through the connections described the required lateral tipping movements to the jack.

Longitudinal tipping movements are imparted to the jack and the shoe by swinging the jack supporting yokes 50 and 48 horizontally, thereby imparting movements to the lower end of the jack spindle laterally of the machine. The required swinging movements are imparted to the jack supporting yokes by means of a cam actuated bell crank lever 76 pivoted on the shaft 56 through a link 78 connecting the forwardly extending arm of the bell crank lever with an arm 80 on the yoke 48. A cam roll supporting lever 82 is pivoted at one end to the laterally extending arm of the bell crank 76 and is connected at its other end by a link and arm similar to the link 68 and arm 70. The lever 82 carries a cam roll which engages in a cam groove 84 in the cam disk 74.

The lateral turning movements of the jack and the shoe are produced by imparting turning movements to the wheel 44. The required turning movements are imparted to the wheel by means of a cable 86 passing about the wheel within a groove in the periphery thereof and secured from slipping about the wheel. The part of the cable leading rearwardly from the left side of the wheel 44 extends about a pulley 88 mounted upon a stud 90 secured in the yoke 50 thence extends to the right about a pulley 92 mounted on a stud secured to the arm 54 and thence about a grooved segment 94 rotatably mounted on a vertical shaft 96 and is secured at its end to the forward part of the segment. The

part of the cable leading rearwardly from the right side of the wheel 44 extends about a second pulley 98 mounted on the stud 90 and thence extends to the left about a pulley 100 and over a pulley 102 both mounted on the frame of the machine. To the end of this part of the cable is secured a weight 104 which operates to keep the cable taut at all times. Swinging movements are imparted 10 to the segment 94 by means of a gear segment 106, secured to the hub of the grooved segment 94 and a cam lever 108 mounted on the vertical shaft 56 upon the forwardly extending arm of which is carried a gear segment 110 meshing with the gear segment 106. The laterally extending arm of the cam lever 108 carries a cam roll engaging a cam face formed 15 on a cam disk mounted on the pattern cam shaft 75.

20 Mechanism for actuating the jack to impart feeding movements to the shoe comprises a lever 112 hereinafter termed the "feeding lever", pivoted on a stud 114, carried by a bracket 116, secured to the frame of the machine and a link 118, connecting the lever with the forward or toe end of the jack. The lever 112 is actuated by means of a lever 120, which is substantially triangular in shape, and is pivotally connected at 122 with the lever 112. The triangular lever 120 is pivoted at 124 to one end of a hanger 126, the other end of which is pivoted at 128 to a lever 130, pivotally mounted on a fixed stud 132. This lever 130 is hereinafter termed, the "fulcrum-carrying lever". The triangular lever 120 is actuated from the pattern cam shaft through connections comprising an intermediate lever 134, pivotally mounted on the machine frame, and a link 136 connecting the lever 134 with the rear end of the triangular lever 120. The intermediate lever 134 is connected by a link 138 with the laterally extending arm of a bell crank lever 140, pivoted on the shaft 56. A cam roll is mounted on this arm of the bell crank lever, and is arranged to engage a cam face 142 formed on a cam disc 144, secured to the pattern cam shaft. A cable 146 is attached at one end to the feeding lever 112, and extends from said lever over a pulley 148 under a pulley 150, and over a pulley 152, all mounted on the frame of the machine. A weight 154 is suspended at the end of the cable.

55 The cam face 142 is so formed that the triangular lever 120 is actuated to move the feeding lever 112 and through said lever to actuate the jack to feed the shoe at a substantially uniform speed past the devices for operating on the shoe. To enable this mechanism for actuating the jack to feed the shoe, to impart the proper feeding movement to the jack for shoes of different sizes, the movement of the triangular lever 120 and the movement imparted thereby to the feeding lever 112 is adjusted to accord with the size

of the shoe placed in the machine. At the time when the shoe is placed in the machine, the fulcrum-carrying lever 130 is unlocked so that it may be adjusted about its axis. When a shoe is placed in the machine in correct position for the starting of the seam, the feed lever 112 will be adjusted through the connections between said lever and the jack in a position depending upon the size of the shoe. The adjustment of the feeding lever 112 thus produced will affect the proper adjustment of the fulcrum of the triangular lever 120.

59 The driving mechanism for the sewing cam shaft comprises a driving shaft 156 upon which is mounted a fast pulley 158 and a loose pulley 160. This shaft carries a bevel gear 162 which meshes with a bevel gear 164 mounted on the upper end of a vertical counter-shaft 166. Fixed upon the counter-shaft 166 is a disk carrying the driving member 168 of a friction clutch, the driven member of which indicated at 170 is carried by a sleeve 172 loosely mounted on the counter-shaft. The sleeve 172 also carries a spiral gear 174 meshing with a spiral gear 176 formed on a sleeve mounted on the sewing cam shaft to rotate therewith. During the sewing operation the members 168 and 170 of the friction clutch are engaged and the sewing cam shaft 34 is driven at a speed depending upon the speed of the driving shaft 156.

64 The pattern cam shaft is driven through a spiral gear 178 journaled on a shaft 180 and meshing with a spiral gear 182 secured to the upper end of the pattern cam shaft. The spiral gear 178 is held from movement longitudinally on the shaft 180 and the shaft is slidably mounted in bearings in sleeves 184 and 186 journaled in the frame of the machine. The sleeve 184 carries at one end a bevel gear 188 and the sleeve 186 carries at one end a bevel gear 190, these gears intermeshing with an intermediate bevel gear 192 secured to the lower end of a vertical counter-shaft 194 arranged in alignment with the counter-shaft 166 but capable of being rotated independently of said shaft. The spiral gear 178 is adapted to be clutched either to the bevel gear 188 or to the bevel gear 190, the respective bevel gears and the spiral gear being provided with inter-engageable clutch projections. The spiral gear 178 may be shifted longitudinally to clutch the same either to the bevel gear 188 or to the bevel gear 190 by the longitudinal movement of the shaft 180 in its bearings in the sleeves 184 and 186. The shaft 180 may be shifted longitudinally by means of a lever 196 pivoted on a stud 198 and connected by a link 200 with a block 202 secured to one end of the shaft 180. To enable the lever 196 to be actuated to shift the shaft 180 and to be held in adjusted position an operating lever

204 is pivoted to an arm of the lever 196 by means of a stud 206 and carries a spring pressed latch pin 208 for engagement with any one of a series of openings 210 in a gage plate 212 formed on the frame. During the sewing operation the spiral gear 178 is clutched to the bevel gear 190 and the pattern cam shaft is then driven from the bevel gear 190 through the spiral gear 178 in a clockwise direction. The spiral gear 178 is clutched to the bevel gear 188 to drive the pattern cam shaft in the reverse or in a counter-clockwise direction only for the purpose of adjusting the pattern cam shaft angularly to enable the cam disks to be removed from the shaft. 5 70 75 80

During the sewing operation the bevel gear 190 is driven to drive the pattern cam shaft in definite timed relation to the sewing cam shaft by mechanism acting to drive the sleeve 186. This mechanism comprises a gear 214 secured to the outer end of the sleeve 186, a train of gears connecting the gear 214 to an obliquely arranged sleeve 216 journaled in the machine frame, an obliquely arranged shaft 218 in axial alignment with the sleeve, spiral gears 220 and 222, connecting the oblique shaft 218 and the sewing cam shaft 34, and a variable speed driving mechanism 25 85 90 95 connecting the shaft 218 and sleeve 216. The variable speed mechanism between the shaft 218 and sleeve 216 comprises a ratchet wheel 224 secured to the sleeve 216, and a series of spring pressed driving pawls 226 respectively pivoted upon oscillatory levers 228, pivotally mounted upon a disc 230 secured to the shaft 218. The angular position of the pawl-carrying levers 228 on their respective pivot studs is controlled by means of a non-rotating ring 231 secured to the upper end of a rock shaft 232 and having a circular groove 234 in which engage rolls 236 mounted on the respective pawl-carrying levers. With this construction the speed at which 100 105 110 115 120 125 130 the ratchet wheel 224 is driven by the pawls 226 may be varied by adjusting the ring about the axis of the rock shaft 232. During the sewing operation the pattern cam shaft is driven from the ratchet wheel 224 through the connections described between the ratchet wheel and the cam shaft 75. The ring 231 is adjusted to adjust the speed at which the pattern cam shaft is driven from the ratchet wheel 224 in accordance with the size of the shoe to be sewn by the placing of the shoe in the machine in position for the starting of the seam. The ring 231 is adjusted upon the placing of the shoe in the machine in position to start the seam by the adjustment 60 of the rock shaft 232 effected through an arm 238 secured to the lower end of the rock shaft, and a link 240 connected at one end by a universal joint with a rearwardly extending arm on the fulcrum carrying lever 65 130 and at the other end by a universal joint with the arm 238. It will thus be seen that the adjustment of the lever 130 produced upon the placing of the shoe in the machine in position to be sewn not only adjusts the fulcrum of the lever 120, but also adjusts the speed of the pattern cam shaft in accordance with the size of the shoe. This adjustment of the speed of the pattern cam shaft times the jack actuating feeding mechanism relatively to the shoe engaging feeding devices so that the jack will be moved by said mechanism to feed the shoe at the same rate that the shoe is normally fed by said devices and will also time the position changing mechanism relatively to the shoe engaging feeding devices. 70 75 80

The members 168 and 170 of the main driving clutch are engaged to start the machine by means of a treadle 242, a lever 244, a treadle rod 246 connecting the treadle with the lever, and connections not shown between the lever and the sleeve 172 through which the sleeve is elevated to engage the driven clutch member 170 with the driving clutch member 168 upon the depression of the treadle. After the last shoe has been placed by the operator on the jack and has been located in a predetermined position on the jack the operator inserts the shoe in the machine with the channel guide roll 30 within the channel of the insole at the proper point for the starting of the seam, and engages the members of the main driving clutch by depressing the treadle. During the sewing operation the members 168 and 170 of the main driving clutch are held in engagement by means of a latch acting on certain of the connections intermediate the lever 244, and the sleeve 172 and the machine is driven at a speed depending upon the speed of the driving shaft 156. When the sewing operation is completed, this latch is thrown out, the members of the main driving clutch are disengaged, and the machine is stopped through the action of automatically acting devices. The mechanism for controlling the throwing out of the latch and the throwing in of the stopping devices is actuated and controlled by a cam carried by one of the cam disks mounted on the pattern cam shaft. When the machine has been stopped at the conclusion of the sewing operation the operator manipulates the jack to disengage the channel guide roll 30 from the channel of the insole and then severs the thread intermediate the thread handling devices and the shoe. Then while holding the jack with the shoe disengaged from the machine, the operator throws in a clutch mechanism which connects the shaft 194 directly with the shaft 166 to drive the pattern cam shaft independently of the sewing cam shaft to bring the jack to its initial or starting position. During the rotation of the pattern cam shaft the jack is turned through sub-

stantially half a revolution in a direction reverse to that in which it is turned during the sewing operation. When the pattern cam shaft has described substantially a complete revolution from the point at which it started at the beginning of the sewing operation, thereby restoring the jack to starting position, this clutch mechanism is automatically thrown out of operation.

10 The mechanism for connecting the shaft 194 directly with the shaft 166 to drive the pattern cam shaft independently of the sewing cam shaft to bring the jack to starting position comprises a roll or Horton clutch 248, the driving member of which is secured to the lower end of the shaft 166, and a clutch dog 250 mounted on the upper end of the shaft 194 and arranged to engage the driven member of the roll clutch. During the sewing 20 operation the devices for controlling the engagement and disengagement of the roll clutch are held in position to maintain the roll clutch out of operation by means of a latch 252 secured to the rear end of a stud 254 mounted in a bearing in the frame to the forward end of which is secured an operating handle 256. In throwing the roll clutch into operation, the operator grasps the operating handle 256 and swings the same to the right, thereby throwing 30 the latch 252 out of operating position. When the pattern cam shaft has described substantially a complete revolution from the point at which it started at the beginning of the sewing operation, the devices for controlling the engagement of the roll clutch are actuated to throw out the clutch through connections from a cam carried by one of the cam disks on the pattern cam shaft.

35 The locking mechanism for locking the lever 130 in position during the sewing operation comprises a rod 258 pivotally connected at its forward end with the lever 130 and engaging in a sleeve 260 pivoted on a stud 262 secured in the frame of the machine, and a pair of locking levers 264 pivoted to the sleeve upon studs 266 and formed with cam-shaped ends arranged to engage the rod 258. The outer ends of the locking levers 264 carry pins 268 engaging in slots formed in the 40 opposite ends of a crossbar 270 to the central part of which is pivotally connected a sleeve 272 having a yielding connection through a coiled spring 274 with a rod 276 engaging in the sleeve. The right hand end of the rod 276 is pivotally connected with the upper end of a lever 278. Upon the depression of the treadle to start the machine, the lever 278 is actuated through certain of the connections intermediate the lever 244 and the sleeve 45 272 to swing the upper end of the lever 278 to the right and thereby move the rod 276 longitudinally to the right to actuate the locking levers 264 to lock the rod 258 in the sleeve 260. The lever 278 is held in locking position by means of a spring pressed latch pin.

This latch pin is controlled through certain connections intermediate the latch 252 and the roll clutch 248 so that as the roll clutch is thrown into operation the latch pin is actuated to release the lever 278 allowing the upper end of the lever to swing to the left to unlock the rod 258 and the lever 130. Thus when the parts of the machine have been brought to rest in positions ready for the reception of another shoe, the lever 130 is unlocked so that it may be adjusted by the placing of another shoe in the machine in position for the starting of a seam.

50 The inseam trimming machine illustrated in Figs 10 to 23 is similar to the inseam sewing machine herein before described in comprising mechanism for acting on the shoe which as a whole is fixed in position, a shoe supporting jack, shoe guiding devices including a guide which engages the channel of the sole, and a pattern cam shaft and suitable connections for moving the jack so as to tip and turn the shoe to locate the inseam trimming cut in the desired position with relation to the 55 stitches of the inseam, as the point of operation of the trimming mechanism is transferred around the shoe. The construction and arrangement of the parts for supporting and moving the shoe are, however, somewhat different from those of the inseam sewing machine. Also the inseam trimming machine is provided with an auxiliary mechanism which is thrown into action at the completion of the inseam trimming operation as the inseam trimming mechanism is stopped, and which acts through suitable devices to disengage the shoe from the inseam trimming mechanism and move the jack away from the inseam trimming mechanism and restore it to its 60 original position.

65 The inseam trimming machine is provided with a crown shaped trimming knife indicated at 280, a crease guide 282 for engaging in the crease between the welt and the upper of a shoe, a channel guide 284 consisting of a roll having a conical lower end for engagement in the channel of the insole, and a member 286 arranged to engage the inner edge of the welt and hold it up to the trimming knife.

70 The trimming knife is secured to a sleeve 75 journalled on a shaft 288 mounted in an adjustable carriage 290, and is driven from a shaft 292, which constitutes the main shaft in the head of the machine, through a cross shaft mounted in the knife carriage, and bevel gears connecting the cross shaft with the shaft 292 and with the sleeve to which the knife is secured. The knife carriage 290 is mounted for adjustment to adjust the knife radially so as to regulate the depth of 80 cut and also to adjust the knife in the direction substantially parallel with the lower side of the knife to compensate for the grinding away of the knife edge.

85 The channel guide roll 284 is rotated so 90

that it tends to feed the shoe. The roll is mounted on the lower end of a shaft journaled in a bearing in a hanger 294 pivoted on bearing pins 296 to swing about a horizontal axis. The roll shaft carries a gear meshing with a gear 298 mounted on the lower end of a shaft 300 journaled in the hanger 294. The shaft 300 is connected at its upper end by a universal joint with the lower end of a shaft 302 journaled in a bearing in the frame. To the upper end of the shaft 302 is secured a spiral gear 304 meshing with spiral gear teeth 306 formed on a double gear wheel 308 mounted on the main shaft 292. The mounting of the hanger 294 upon the bearing pins 296 allows the roll 284 to move toward and from the crease guide 282 in accordance with variations in the thickness of the material between the roll 284 and the guide. During the normal operation of the machine the hanger 294 is acted upon by a coiled spring 310 connected with a rearwardly extending arm 312 on the hanger which tends to swing the hanger in a direction to force the roll 284 toward the crease guide 282 so as to maintain the roll and guide in guiding engagement with the shoe.

The welt of the shoe is beaten out as it is advanced across the upper surface of the guide 282 by means of a vibratory beater 314, which acts on the flesh side of the welt and is formed on the forward end of a lever 316 pivoted on a stud 318. The rear end of the lever 316 is connected by means of a link 320 with the lower end of an actuating lever 322 pivoted at 324 on the frame. The upper end of the lever 322 embraces a three point cam 326 mounted on the main shaft 292. The parts are constructed and arranged so that during the swinging movement of the lever 322 in each direction the median line of the lever or the line connecting the center of the pivot 324 with the center of the pivotal connection between the link 320 and the lever 322 is carried from a position on one side of the center of the pivotal connection between the link 320 and the lever 316 to a position on the other side of said center. With this construction the beater 314 is very rapidly vibrated even with a relatively low speed of rotation of the main shaft 292.

The machine is provided with a rotary grinding disk or wheel 328 mounted so that it may be moved into and out of operative position with relation to the knife. The grinding wheel is secured to the forward end of the shaft journaled in a sleeve 330 which is mounted for a longitudinal movement on bearings in the frame to carry the grinding wheel into and out of position to engage the knife edge. The mechanism for adjusting the sleeve longitudinally comprises a rod 332 secured to the rear of the sleeve and a spiral pinion 334 journaled in bearings in arms 336 on the frame and threaded on the rod. The

pinion 334 is engaged by a corresponding pinion 338 mounted on the inner end of a shaft 340 having bearings in the frame to the outer end of which is secured a hand-wheel 342 by which the shaft may be rotated manually to adjust the sleeve 330.

The grinding wheel is driven from the main shaft 292 through connections comprising a gear 344 secured to a shaft 346 and meshing with a gear on the shaft of the grinding wheel a spiral gear 348 on the shaft 346 and spiral gear teeth on the gear wheel 308 meshing with the spiral gear 348.

The driving mechanism for the main shaft 292 (see Figs. 17 and 18) comprises a driving shaft 352 adapted to be connected at its upper end with a suitable power shaft and carrying a driving member 354 of a friction clutch. The driven member of the clutch indicated at 356 is carried by a sleeve 358 loosely mounted on the shaft. The sleeve 358 also carries a spiral gear 360 which meshes with a spiral gear 362 fixed to the main shaft 292. During the operation of the machine in trimming the inseam and beating out the welt of a shoe the members 354 and 356 of the main driving clutch are engaged and the main shaft 292 is driven through the spiral gears 360 and 362 at a speed dependent upon the speed of the driving shaft 352.

The jack for supporting the lasted shoe during the operation of the machine (see Figs. 10 and 11) is the same as the jack of the inseam sewing machine and comprises a heel supporting arm 364 and a toe supporting arm 366 mounted upon a spindle 368. The lower end of the jack spindle is secured to a hemispherical shell or casing as in the inseam sewing machine which is connected by means of a gimbal joint with a wheel 370 mounted to rotate on a vertical stud 372. The stud 372 is secured in a casing carried at the forward ends of supporting arms 374, (see Figs. 16 and 19) the rear ends of which are secured in a carrier 376 pivoted to swing vertically at the upper end of a support 378. The support 378 is pivoted at 380 and 382 on a second support 384 to swing laterally of the machine. The support 384 is mounted on pivot studs 386 to swing forwardly and rearwardly. The jack spindle is yieldingly supported vertically by means of a coiled spring 388.

During the operation of the machine on the shoe the shoe is held positively to the machine at all times by the guides engaging the shoe at the point of operation and, chiefly, by the action of the channel guide roll 284 and the crease guide 282. Relatively slight vertical movements are imparted to the jack and the shoe by the cooperative action of the spring 388 and the guides engaging the shoe. The required tipping movements are imparted to the jack and thereby to the shoe by de-

5 vices acting on the jack spindle to move the lower end of the spindle in horizontal directions forwardly, rearwardly and laterally of the machine, and the turning movements are imparted to the shoe by devices acting on the jack spindle to rotate it. Because of the fact that the shoe is held at all times at the point of operation by the guides engaging the shoe, the tipping and turning movements are 10 caused to take place about these guides as a fulcrum, or about the point of operation.

15 The support 384 is swung forwardly and rearwardly to impart lateral tipping movements to the shoe by means of a cam lever 390 pivoted on a shaft 392 and a ball-ended link 394 connecting one arm of the lever with the support 384. The support 378 is swung laterally to impart longitudinal tipping movements to the shoe by means of a cam lever 396 20 pivoted on the shaft 392 and a link 398 connecting one arm of the cam lever with an arm on said support. The wheel 370 is rotated to impart lateral turning movements to the jack by means of a cable 400 passing about 25 the wheel, about guide pulleys 402 and 404 mounted on the carrier 376 and over a stationary guide pulley 406. One end of the cable is secured to a pulley 408 mounted to rotate on a stud 410, and to the other end of 30 the cable is attached a weight 412. The rotative movements of the pulley 408 are produced and controlled by means of a cam lever 414 pivoted on the shaft 392 and connected to the pulley 408 through a gear segment and 35 a gear 418. Each of the cam levers 390, 396 and 414 carries a cam roll arranged to engage the periphery of one of a series of cam disks mounted on a pattern cam shaft 420.

40 The shoe is fed during the operation by the rotary movement of the guide roll 284 and by mechanism acting to impart feeding movements to the jack. The mechanism for thus actuating the jack (see Figs. 10 and 16) comprises a lever 422 pivoted at 424 on the frame and a link 426 connecting said lever with the toe end of the jack. During the sewing operation on the shoe the feeding lever 422 is swung toward the left to actuate the jack to advance the marginal portion of the shoe bottom past the trimming knife and welt beating devices at substantially the same speed as the peripheral speed of the feeding roll 284. The mechanism for actuating the feeding lever comprises an arm 428 pivoted 45 at 430 on the frame and pivotally connected links 432 and 434 connecting the arm 428 with the feeding lever. The arm 428 is actuated through a link 436 from a cam lever 438 pivoted on the shaft 392 and carrying a cam roll 50 arranged to engage the periphery of a cam disk mounted on the cam shaft 420. The path 50 of the connection between the links 432 and 434 is controlled by an arm 440 pivoted at 442 on a lever 444 hereinafter termed the fulcrum 55 carrying lever which is pivoted at 446 on the

frame. During the operation of the machine the fulcrum carrying lever is locked in position. When a shoe is placed in the machine, however, the fulcrum carrying lever is unlocked and is free to be adjusted in accordance with the size of the shoe. The feeding lever 422 and the fulcrum carrying lever are 60 acted upon by a cable 448 attached at one end to the feeding lever and passing about a pulley 450 mounted coaxially with the lever 444, about a pulley 452 mounted on said lever, and over a pulley 454 mounted on the frame, the cable having a weight 456 attached to the outer end thereof which exerts a constant pull 65 on the cable.

70 The mechanism for driving the pattern cam shaft comprises a gear 458 secured to the upper end of said shaft and arranged to be driven through a train of gears from a gear 460 formed on the lower end of a sleeve 462. (See Fig. 18). The sleeve 462 is driven by 75 a variable speed mechanism similar to that of the inseam sewing machine hereinbefore described comprising a ratchet wheel 464 mounted on a shaft 466 and a series of pawls 468 mounted on oscillatory levers 470 carried by the sleeve. The shaft 466 is driven from 80 a shaft 472 through intermeshing clutch members 474 and 476, the upper member of which is keyed to the shaft 472, and is held in engagement with the clutch member 476 by 85 springs 478. To the upper end of the shaft 472 is secured a spiral gear 480 meshing with the spiral gear 360 through which the shaft 472 is driven in timed relation to the main 90 shaft 292.

95 The oscillation of the pawl carrying levers 470 is controlled by means of a ring 482 adjustably mounted on the frame and formed with a groove in which engage rolls 484 carried by the levers. The position of the ring is controlled through suitable connections from a rock shaft 486. To this rock shaft 100 is secured an arm 488 to which is pivoted one end of a longitudinally movable controller bar 490. The other end of the controller bar is 105 movably supported by a link 492 and a lever 494 pivoted on a stud 496. The latter end of the controller bar is formed with oppositely inclined surfaces 498 leading to a recess 500 adapted to receive a roll 502 mounted on the fulcrum carrying lever 444. When the machine is at rest the controller bar 490 is held in its rearward position by the action of a spring 504, as shown in Fig. 16. Upon the 110 depression of the starting treadle the controller bar 490 is swung forwardly to engage the roll 502 in the recess 500 by means of one or more pins 506 mounted on a longitudinally movable bar 508 and arranged to 115 engage the lever 494.

120 The bar 508 is connected to a treadle in such a manner that upon the depression of the treadle the bar is moved longitudinally to the right, as viewed in Fig. 16, this movement 125

110

115

120

125

130

of the bar operating to cause the engagement of the members 354 and 356 of the main driving clutch to start the machine, as hereinafter described.

Before the depression of the treadle to start the machine the shoe is placed in the machine in the correct position for the starting of the operation, thereby adjusting the fulcrum carrying lever 444 in accordance with the size of the shoe. When the controller bar 490 is 10 swung forwardly, through the engagement of the bar with the roll 502, the bar is adjusted longitudinally in a position corresponding with the position of the fulcrum carrying lever 444 and through the connections described the ring 482 is adjusted to adjust the speed of the cam shaft in accordance with the size of the shoe to be operated upon.

The mechanism for locking the fulcrum carrying lever in position during the operation (see Fig. 16) comprises a rod 510 pivotally connected at one end with the fulcrum carrying lever, and engaging in a sleeve 512 pivoted on a stud 514, and pivoted locking levers 516 arranged to engage the rod. The locking levers are actuated to lock and release the rod 510 by the forward and rearward movement of the controller bar 490 through connections comprising a cross bar 518, a sleeve 520, a coiled spring 522 and a rod 524.

The controller bar 490 is held in forward position during the operation on the shoe by means of a spring actuated pivot latch. As the lever 494 is actuated to swing the controller bar 490 forwardly upon the depression of the treadle, the latch 526 engages a projection on said lever and holds the same in position when the bar 508 returns to its initial position upon the release of the treadle. The latch 526 holds the lever 494 and the controller bar in position during the operation on a shoe and also after the completion of the operation until another shoe is placed on the jack. Upon the placing of another shoe on the jack, the latch is thrown out allowing the controller bar to swing back to its rearward position.

During the inseam trimming operation the members 354 and 356 of the main driving clutch are held in engagement, and the shaft 292 of the inseam trimming mechanism is driven at a speed depending upon the speed of the driving shaft 352. When the operation is completed the members of the main driving clutch are disengaged and the shaft 292 is stopped by automatically acting devices. The mechanism for disengaging the clutch and stopping the shaft 292 is arranged to be thrown into operation automatically at a predetermined point in the operation. The sleeve 358 (see Figs. 16 and 17) is arranged to slide longitudinally of the shaft 352 and carries a brake member 528 arranged to engage a fixed brake shoe 530. The sleeve is normally held in its upper position with the

members of the clutch engaged and with the members of the brake disengaged by means of a coiled spring 532.

The mechanism for moving the sleeve 358 downwardly to disengage the clutch and engage the brake (see Figs. 16 and 17) comprises a bell crank lever 534 pivoted on a stud 536 one arm of which carries a cam roll 538 engaging in a cam groove 540 in the sleeve. A locking pin 542 is mounted to slide longitudinally in a carrier 544 and is arranged to engage in a recess 546 in the other arm of the bell crank lever. The carrier 544 is mounted to slide longitudinally in suitable guides and is acted upon by a coiled spring 548 surrounding a rod 550 which forms part of the carrier and is interposed between the outer end of an adjustable screw threaded sleeve 552 through which the rod slides and a flanged sleeve 554 mounted on the rod. The spring 548 normally holds the carrier in position with a shoulder on the carrier in engagement with the inner end of the sleeve 552. The locking pin 542 is acted upon by a spring which tends to move the same rearwardly into engagement with the bell crank lever 534. During the normal operation of the machine, however, the locking pin is held out of engagement with the bell crank lever so that the lever is oscillated idly by the action of the cam groove 540. In stopping the machine the locking pin 542 is released and is actuated by its spring to engage the recess in the bell crank lever 534, thus locking the lever to the carrier 544. When this occurs the sleeve 358 is moved downwardly to disengage the main driving clutch and engage the brake. In order to render the cam groove 540 effective to move the sleeve downwardly a latch lever 556 is provided to prevent the return of the carrier 544 to its normal position after it is moved longitudinally to the right.

The locking pin is normally held in forward position by means of a bell crank lever 558 pivoted on the machine frame and arranged to engage a collar secured to the locking pin. The lever 558 carries a gear segment which meshes with a gear segment carried by a lever 560 pivoted on a stud 562. The lever 560 is pivotally connected by means of a pin 564 with the upper end of a vertically movable rod 566. This rod also controls the position of the latch lever 556 through the engagement of the rear end of the pin in a slot in the latch lever.

The rod 566 is pivotally connected with a second vertically movable rod 568 which carries at its lower end a collar 570 arranged to be engaged by a lever 572 pivoted at 574 on the frame. The lever 572 is engaged by the right hand end of the bar 508 as said bar is moved to the right by the depression of the treadle and the lever is thereby actuated

to depress the rods 568 and 566. The rods are held in depressed position during the operation on the shoe by means of a latch 576 arranged to engage a projection 578 on the rod. The latch is slidably mounted in guides and is acted upon by a coiled spring 580 which tends to advance the same into acting position. The stopping devices are thus held out of operation by the latch 576 after the starting of the machine, allowing the treadle to be released and the bar 508 to be moved back to its normal position.

When the operation on the shoe is completed the latch 576 is automatically disengaged from the projection 578 on the rod 568, allowing the stopping devices to be thrown into operation. The latch is provided with a V-shaped slot (see Fig. 23) in which is engaged a pin 582 mounted on a lever 584 pivoted on a stud 586. In stopping the machine at the completion of the operation the left hand end of the lever 584 is swung forwardly by automatically acting devices, thereby retracting the latch.

Upon stopping the machine at the completion of an operation on the shoe the shoe engaging guides and welt beating devices are moved relatively to permit the disengagement of the shoe from the same. To this end the roll 284 is swung forwardly and upwardly away from the crease guide 282 and welt edge guide 286 and the crease guide is swung downwardly away from the beater 314. The arm 312 on the hanger 294 is arranged to be engaged by a hook 588 (see Figs. 13 and 14) formed on the upper end of a bar 590, the lower end of which is pivotally connected with one arm of a bell crank lever 592 secured to one end of a rock shaft 594. The crease guide 282 is formed at the forward end of a lever 596 pivoted on the stud 318. The position of the lever 596 is controlled by means of a toggle consisting of pivotally connected links 598 and 600 of which the link 598 is pivotally connected with the lever 596 and the link 600 is rigidly secured to the rock shaft 594. During the normal operation of the machine the lever 592 is held stationary with the hook 588 above the upper side of the arm 312 and with the toggle 598—600 in a straightened condition so that the roll 284 is free to move toward and from the crease guide 282 under the influence of the spring 310 and the crease guide is held rigidly in position. Upon stopping the trimming operation, however, the lever 592 is actuated to depress the bar 590, thereby swinging the hanger 294 to move the roll 284 into the position shown in dot and dash lines, Fig. 13, and breaking the toggle 598—600, thereby actuating the lever 596 to depress the crease guide 282. The mechanism for thus actuating the lever 592 comprises a rock shaft 602, a lever 604 loosely mounted on the rock shaft, a link 606 connecting the latter lever

with the lever 592. The lever 604 is actuated from the rock shaft 602 through connections which allow for considerable lost motion. The rock shaft 602 carries at its right hand end a gear segment which meshes with gear teeth formed on a block 608 secured to the upper end of a rock shaft 610. The block carries an arm arranged to be actuated from an intermittently operating eccentric 612 through an eccentric strap 614 and a pitman 616.

During the normal operation of the machine the eccentric 612 is stationary, and upon stopping the machine the eccentric is rotated through a complete revolution. During this revolution of the eccentric the shaft 602 is turned first in a counterclockwise direction, and then back in a clockwise direction to its initial position. As the shaft is turned in a counterclockwise direction the lever 604 is swung with the shaft. This movement of the lever actuates the lever 592 to move the channel guide roll away from the crease guide and welt edge guide and to depress the crease guide. To hold the channel guide roll and the crease guide in position as the rock shaft 602 is turned back in a clockwise direction the lever 604, after being swung by the counterclockwise movement of the shaft, is held from return movement by the engagement of the forwardly extending arm of a latch lever 618 (see Fig. 13) with the upper end of said lever.

After the guides and welt beating devices are actuated to permit the disengagement of the shoe, the jack is swung forwardly out of operating position and is held in forward position during the turning movement imparted thereto to restore the same to its initial position. The mechanism for swinging the jack forwardly out of operating position is also operated from the eccentric 612. This mechanism (see Figs. 16, 19 and 20) comprises a rock shaft 620 rigidly connected with the rock shaft 610, an arm 622 secured to the rock shaft and carrying a gear segment, a cooperating gear segment secured to a rock shaft 624, a lever 626 mounted to turn loosely on the latter rock shaft and connected therewith by a spring, and a pin 628 mounted in one of the gear segments and arranged to engage the lever 626 to swing the same forwardly. A slide 630 is mounted in the lever 626 and is arranged to engage a projection 632 formed on a bar 634 connected at its forward end with the jack and supported at its rear end by a pivoted arm 636. During the normal operation of the machine the lever is held in its rearward position as shown in Fig. 16. As the eccentric 612 is thrown into operation upon stopping the machine the lever 626 is swung forwardly during the first half revolution of the eccentric into the position shown in Figs. 19 and 20. During this movement of the lever 626 the slide 630 engages the projec-

tion 632 on the bar 634 and the bar is actuated to swing the jack forwardly out of operating position. The lever 626 after having been swung into forward position is held from return movement by means of a spring pressed latch 638. The jack is held in forward position during the turning movement imparted to the jack to restore the same to starting position and during the removal of the shoe from the jack. The latch is thrown out, however, when another shoe is placed on the jack allowing the lever 626 to swing back to its rearward position. As the shoe is placed on the jack a sharp downward push or blow is delivered to the shoe to seat the last pin in the last pin hole in the last. This forces the shoe and jack downwardly. The downward movement thus imparted to the jack depresses the slide 630 which is connected with the latch by a rod 640 and the latch is thereby thrown out.

The latch 526 is thrown out to release the lever 494 and the controller bar 490 by the swinging movement of the lever 626 from its forward to its rearward position through the engagement of a spring pressed plunger mounted in the lever 626 with the latch. As the latch 526 is thrown out the controller bar 490 is swung back to its rearward position and the locking devices for the fulcrum carrying lever 444 are actuated to unlock said lever.

The driving mechanism for the eccentric 612 (see Figs. 17 and 18) comprises a shaft 642 which is driven through a train of gears 352 at a relatively slow speed. A clutch member 644 is splined to the shaft 642 and is arranged to engage a corresponding clutch member 646 secured to the eccentric. The position of the clutch member 644 on the shaft 642 is controlled by means of a lever 648. Upon stopping the machine the lever 648 is actuated to move the clutch member 644 upwardly into engagement with the clutch member 646.

The mechanism for actuating the lever 648 comprises a rod 650 pivotally supported upon an arm 652 secured to one end of a rock shaft 654. To the other end of the rock shaft is secured an arm 656 carrying a gear segment meshing with a gear segment carried at the end of one arm of a bell crank lever 658 pivoted at 660 on the frame. The other arm of the bell crank carries rolls engaging between the flanges on the sleeve 554. Through the connections described as the lock bolt carrier 544 is moved to the right upon stopping the machine, the rod 650 is lifted and as the lock bolt carrier moves back to the left the rod is depressed. The rod is formed with a projection 662 which is normally located behind a projection 664 on the forward end of the lever 648. The lower end of the rod engages between two pins 666 mounted on a lever 668 pivoted on the stud 586 above the

lever 584 and normally held in central position with relation to the lever 584 by means of spring pressed plungers, 679. As stated above, in stopping the machine after the completion of the operation on the shoe the left hand end of the lever 584 is swung forwardly. During this movement of the lever 584 the rod 650 and the lever 668 are held from forward movement by the engagement of the projection 662 with the projection 664. As the rod is lifted by the movement of the lock bolt carrier the projection 662 is carried above the projection 664 and the lever 668 and the rod are then swung forwardly by the action of one of the spring pressed plungers 679, thereby locating the projection 662 above the projection 664. Then as the rod is depressed by the movement of the lock bolt carrier, the lever 648 is actuated by the engagement of the projection 662 with the projection 664 to engage the clutch member 644 with the clutch member 646. Through the engagement of these clutch members the eccentric 612 is driven through a complete revolution before the machine finally comes to rest.

As the eccentric completes a single revolution the lever 668 and the rod 650 are swung rearwardly to disengage the projection 662 from above the projection 664, and the lever 648 is then moved back to its normal position thereby moving the driving clutch member 644 downwardly out of engagement with the driven clutch member 646. The mechanism for thus swinging the lever 668 rearwardly (see Fig. 23) comprises a lever 672 pivoted on a stud 674 and connected with the lever 668 through intermeshing gear teeth. The lever 672 carries a pivoted dog 676 having a projection arranged to be engaged by a stud 678 mounted on an arm 680 secured to the rock shaft 620. The dog 676 has a limited pivotal movement with relation to the lever 672 and is normally held by a spring in engagement with a stop formed on the lever as shown in Fig. 23. When the lever 668 is swung forwardly the projection on the dog 676 is carried into position to be engaged by the stud 678.

As the arm 680 is swung to the left during the first part of the revolution of the eccentric, the stud 678 engages the projection on the dog and swings the dog on its axis until the stud passes by the projection. As the arm 680 swings back to the right during the last half revolution of the eccentric the stud 678 again engages the projection on the dog. The engagement of the dog with the stop on the lever 672 prevents the dog from swinging under the action of the stud and the lever 672 is actuated to swing the lever 668 rearwardly to its normal position. This movement of the lever 668 swings the rod 650 rearwardly, thereby disengaging the projection 662 from above the projection 664.

The mechanism for swinging the lever 584 forwardly to stop the machine (see Fig. 16)

comprises a lever 682 pivoted at 684 on a bell crank lever 686 and a link 688 connecting the lever 682 with the lever 584. At a pre-determined point in the operation of the machine, the outer end of the lever 682 is engaged by a contact plate 690 secured to the gear 458, and is swung rearwardly. The movement of the lever 682 moves the lever 584 forwardly to stop the machine.

- 10 During the operation of the machine on the shoe the pattern cam shaft is driven through the greater portion of a revolution, and after the main driving clutch has been disengaged and the inseam trimming and 15 welt beating mechanisms have been stopped at the completion of the operation, the pattern cam shaft is driven in the same direction as during the normal operation of the machine through the remaining part of a 20 revolution to bring the same to its initial or starting position. During this movement of the pattern cam shaft, after the operation on the shoe has been completed, the jack is turned through half a revolution in a direction 25 opposite to the direction in which it is turned during the normal operation to bring the jack to its initial or starting position. The pattern cam shaft is rotated through the remaining part of a revolution after the 30 disengagement of the main clutch by the end-wise movement of the lever 682 imparted thereto by the movement of the bell crank lever 686.

The invention having been thus described, 35 what is claimed is:—

1. The method of making shoes which comprises presenting a lasted shoe successively to two different operating means comprising respectively an inseam sewing mechanism 40 and an inseam trimming mechanism, guiding the shoe during each operation to cause the point of operation to follow a predetermined outline, and imparting predetermined relative tipping positioning movements to 45 the shoe and the operating means as the point of operation is transferred around the shoe to locate the inseam and the inseam trimming cut in predetermined relation to the shoe sole and to each other.
- 50 2. The method of making shoes which comprises presenting a lasted shoe successively to two different operating means arranged to operate about the bottom margin of the shoe, guiding the shoe during each operation by 55 engaging a guiding device in the inseam channel of the sole, and imparting predetermined relative tipping positioning movements to the shoe and the operating means as the point of operation is transferred 60 around the shoe to locate the paths of the operating means in predetermined relation to the shoe sole and to each other.
- 65 3. The method of making shoes which comprises presenting a lasted shoe successively to two different operating means comprising

respectively an inseam sewing mechanism and an inseam trimming mechanism, guiding the shoe during each operation by engaging a guiding device in the inseam channel of the sole, and imparting predetermined relative tipping positioning movements to the shoe and the operating means as the point of operation is transferred around the shoe to locate the inseam and the inseam trimming cut in predetermined relation to the shoe sole and to each other.

4. The method of making shoes which comprises presenting a lasted shoe successively to two different operating means comprising respectively an inseam sewing mechanism and an inseam trimming mechanism, guiding the shoe during each operation by engaging a guiding device in the inseam channel of the sole and imparting predetermined tipping positioning movements to the shoe as the point of operation is transferred around the shoe to locate the inseam and the inseam trimming cut in predetermined relation to the shoe sole and to each other.

In testimony whereof we have signed our names to this specification.

LAURENCE E. TOPHAM.
ALFRED R. MORRILL.
